T. P. Anderson,

Water-Wheel Gate.

Patented Dec. 23, 1833.

Dec 23, 1833 111

Timothy P. Anderson of Haverhill, county of Worcester,
commonwealth of Massachusetts

Letters Patent

The Schedule referred to in these Letters Patent and making part
of the same, containing a description in the words of the said Timothy P.
Anderson himself of his improvement in the economy of Water power by
means of a graduated sprout.

To all people to whom these Presents shall come:
Be it known, that I, Timothy P. Anderson of Haverhill in the
county of Worcester and commonwealth of Massachusetts,
have invented a new and useful improvement in the economy of
water power by means of a graduated sprout or trough; and that the
following is a full and exact description of the construction & operation
of the same as invented or improved by me & specified in the words
following. To wit:

The flume containing the water may be conducted
to & in the usual manner. The shaft of the water wheel stands per-
pendicularly & near the lower end of it are firmly attached and built
to. The buckets which I have made use of, are about twelve inches
in width and placed upon the shaft in this way: they lap over each
other at the ends and the space between the laps is about two inches.

The sprout conducting the water from the flume is as wide as the
buckets and passes round the shaft in such manner that the upper
edge of the buckets compose the lower edge of the sprout. From the
point at which the water strikes the first bucket, the sprout begins
to diminish in its depth (its width being uniform) until it has
passed entirely round the wheel - the top and sides of the sprout
are made sufficiently firm to support the pressure of the water -
The only place for the water to escape from the sprout is thro' its laps
in the buckets - And as the sprout diminishes in its depth the pressure
of the water increases as great as it is, and as on the first bucket it is upon
the buckets at the same time.

Dec 23, 1833

Explanation of the Drawing

AAAA Frame of the Flume Bc Slump a shaft or spout, conducting the water to the wheel, of a top or upper side of the wheel, or shaft-mills buckets attached to the shaft & combined in the spout etc. - Operation of the Machine - When the water is permitted to pass out of the flume into the spout on the whole shaft is immediately filled and the impetus of the water when the buckets pass the shaft in motion.

There is a small space of four eight between my wheel and a common hub-wheel, but the difference consists in the manner in which the water leaves the buckets - In the hub-wheel the water leaves the buckets at almost a right angle, but in mine it leaves them in almost directly the opposite direction to its course - And in this way as the water flows in a direction nearly opposite parallel with the buckets and cannot escape, excepting between them, the first action of the water is direct impulse and that produced by the contrary direction is reaction, and these, it is believed make a valuable saving of water power.

All I claim as my invention is the graduated spout or trough as above described & its applicability as applied by me -
